AIR CONDITIONING APPARATUS

Charles B. Grady, West Orange, N. J.

Application June 29, 1934, Serial No. 732,958

7 Claims. (Cl. 261—92)

This invention relates to air conditioning apparatus, adapted for the treatment of air in one or more of the following respects, namely filtering it, controlling its temperature or cooling it, 5 washing it and controlling its moisture or humidifying it and medicating it; and some of the principles hereof may be useful for the treatment of gases other than air. In some aspects a new method is involved.

10 The apparatus of this invention is useful for example for the conditioning of air in dwelling or other rooms, individually or in groups. As specifically herein shown the apparatus is especially of utility in summer to cool, wash and filter and to 15 humidify or dehumidify the air of closed rooms, such as sleeping rooms occupied for example by persons subject to hay fever, pollen asthma and similar afflictions. The great value of this treatment and apparatus for such patients is that 20 while indoors, especially through each night, extensive recovery from the trouble may be effected and the resistance built up to such high point that a reasonable amount of subsequent daily outdoor exposure to the pollen and other conditions, and even strenuous exercise and exertion, 25 may be had without troublesome effect. The apparatus however is universal in its adaptation to advantageous use in winter by changes in operation and control.

30 I have already shown gas treating or air conditioning apparatuses in several copending applications, Serial Nos. 630,175 filed August 24, 1932, (issued as U. S. Patent No. 2,004,108 on June 11, 1935) 652,251 filed January 18, 1933, (issued as 35 U. S. Patent No. 2,013,270 on September 3, 1935) and 713,086 filed February 27, 1934, to which reference may be had for various details not herein fully disclosed; and the present invention may be considered as an improvement on the apparatuses 40 of said prior applications.

For the purposes thus outlined the objects of the present invention are to afford a practical, compact, quiet and relatively inexpensive apparatus adapted for use in dwellings and elsewhere for 45 the conditioning of air in closed rooms in an efficient and economical manner. Another object is to render it convenient in operation and regulation and readily adaptable to use in winter or summer. Other and further objects and advantages of the invention will be explained in the 50 hereininafter following description of an illustrative embodiment of the invention or will be apparent to those conversant with the subject.

To the attainment of such objects and advantages the present invention consists in the novel

air conditioning apparatus and the novel features of combination, arrangement and construction herein described or illustrated.

In the accompanying drawing Figure 1 is a front elevation, largely in longitudinal vertical section, of an air conditioning apparatus embodying the features of the present improvement.

Fig. 2 is a vertical transverse section along the line 2—2 of Fig. 1 and looking from the right end of the apparatus.

First will be described certain of the general apparatus parts herein some of which correspond with my said prior applications. A main enclosure or cabinet 10 is shown built up of a bottom wall 11, an end wall 12 at the inlet end, an end wall 13 at the outlet end and side walls 14. At the top is shown a cover plate or wall 15, although this may be omitted and the filter housing to be described serve as a cover to the main or lower enclosure. The lower part of the enclosure 10 constitutes a water vessel 16 and this is filled with water up to the water line 17. In summer for example the water may be maintained or supplied at a temperature in the neighborhood of 42° to 55° F., and it may be resupplied or its temperature controlled in the hereinafter described manner or otherwise. In the wall 12 is shown an air inlet opening or port 18, for indoor air from the room the air of which is being conditioned. At the inlet end in the cover wall is shown a second inlet port 20, the purpose of which will be hereinbelow described. In the left end wall 13 is an outlet or port 21 delivering conditioned air into the room. By these ports room air is circulated through the apparatus and back into the room. A damper may be provided at the outlet port if desired to afford control of the air delivery and recirculation.

Preferably the air is driven through the enclosure, and there is shown, upon a cross brace 24, a motor 25 driving an air blower or other fan 26, so that the air received at the inlets 19 and 20 is forced through the enclosure.

In order to cause a reaction between the forced air and the water within the enclosure the air is shown as passing through a casing 28 constituted of a wall enclosing an air passage, at the initial or right end of which is located the fan 26. The wall 28 slants downwardly so that the air passage converges, giving accentuated speed of flow. The wall 28 preferably extends below the water level and its submerged portion 29 may take any convenient shape, the wall portion above the water and the surface of the water enclosing the air passage. The air passage is continued leftward

by reason of an arched baffle or wall 30 which may be mounted upon and dependent from the cover plate 15, this also having a portion 31 submerged below the water level.

5 In the air passage defined by the wall 28 and baffle 30 is mounted a rotary element or wheel 32 which may take part in the washing of the advancing air and the controlling of its temperature and humidity. The wheel 32, as in said 10 prior applications, preferably rotates transversely to the direction of air flow, and may turn at a slow but steady speed by the action of the air traveling through the passage. For this purpose the blades 33 of the rotary element are inclined 15 so as to act as propeller blades, the traveling air causing the movement of the blades. Each blade in turn effects treatment of the air, becoming first submerged, wetted and cooled and thereafter traveling through the air passage so as to act 20 upon the advancing air in the manner described. The partly submerged wheel 32 is shown as having a shaft 34 which turns in the center part of a bracket or bar 35 which for example may be mounted transversely across the right side of the 25 arched baffle 30.

By way of adapting the apparatus to winter use, means arranged for heating the water in vessel 16 is shown, operating like that in application No. 652,251 but here consisting of a heating coil 30 36, for example for steam. The heated water acts to humidify and warm the air passed through the unit as is desirable in winter. An immersed electrical heater would equally serve the purpose, or in some cases water might be heated in the 35 auxiliary tank to be described for automatic circulation into the vessel 16; or, with air conditioning carried on the warming of the room air might economically be effected by independent electric or other heating means. For winter use, 40 when outdoor temperatures may fall below 32°, the auxiliary cooling means to be described may be rendered inoperative, for example by draining the same and the vessel 16, as by a drain cock at the bottom of vessel 16, and the pipes 39 and 45 40 closed by applying caps 42 thereon, shown removed, and refilling the vessel 16.

In order to maintain at approximately any desired temperature the water within the vessel 16, say between 42° and 55° in summer, there is shown 50 in Fig. 2 an auxiliary arrangement preferably located outside of the room under treatment. Thus the enclosure 10 is shown at the inner side of a room wall 37 while the parts to be described may be located outside thereof. These include a separate vessel or tank 38 in which water may stand at the level 17 and may be cooled artificially. A pipe 39 is shown passing through the wall 37 and conducting relatively less cool water from the vessel 16 to the tank 38, while at a lower level a second pipe 40 conducts the relatively cooler water from the tank 38 back to the vessel 16. By cooling the water in the auxiliary tank, or supplying cool water to it gravity will operate to cause an interflow, or automatic circulation, the cool water 55 entering the vessel so as to preserve its cool temperature, the warmer water flowing back into the tank. The tank 38 is preferably outdoors, but may be indoors as in a closet, or even within the room if properly housed and ventilated to prevent escape of refrigerant into the room atmosphere. A protective outside housing 47 is shown 60 ventilated by louvers 48. Instead of a tank for each room a single tank may serve several rooms, connected as described for automatic gravity circulation of cool water to each.

The described arrangement for cooling or refreshing the cool water in the vessel 16 is not always necessary, since the vessel may be supplied at will with very cool water, and the effect thereof may continue for many hours; but when the 5 weather is very warm or humid the described arrangements avoid the necessity of frequent attention and change of water in the vessel.

Within the tank 38 is shown a cooling or temperature controlling means, in the form of a coil 10 43, representative of any means of lowering the temperature of the water in the tank. For example the coil may be supplied with sulfur dioxide, or other refrigerant, or a refrigerated fluid as brine. There is shown an inlet pipe 42 from a 15 refrigerating apparatus or other source to the tank and an outlet or return pipe 45 from the tank. Manifestly the temperature conditions within the tank 38, and therefore within the vessel 16, may be controlled thermostatically in any 20 well known manner; and similarly there may be hygostatic control from the condition of the room air in manner well known.

Having described air washing means, and control of its humidity and temperature there will 25 next be described a cooperative means of filtering the air passed through the apparatus.

In my said prior applications I have indicated in the air path a simple wire mesh, having a certain straining effect on the treated air; and it 30 has been heretofore well known to force air through filters or purifying strata of various kinds to remove pollen, dust and other solid or gaseous impurities. In the present improvement there is shown a special and an advantageous 35 construction of filtering means. This is contained in a housing 50 which for convenience and compactness may be set directly on top of the enclosure 10. The filter housing has a bottom wall 51 resting on the enclosure top wall, and 40 manifestly the latter may be omitted and the former served as the top wall of the enclosure. The bottom wall 51 of the housing 50 is shown as formed with an outlet or port 52 registering with the inlet 20 of the enclosure 10 so as to 45 admit filtered air from the housing to the enclosure. The housing is shown as having a top wall 54 and side and end walls. In the top wall at the left end is an inlet or port 55 to which extends an air duct 56 leading from an outdoor 50 point, so as systematically to draw a certain proportion of outdoor air into the room, under control of a damper 57 adjustable in the duct 56. Preferably also the duct 56 contains an indoor opening controlled by a damper 58, so as to take 55 air from the room and so modify the draft of outdoor air through the duct.

In order that the air entering the housing 50 by the port 55 and leaving it by the port 52 may be filtered the interior of the housing is 60 shown as divided by a partition wall 60 into an inlet compartment 61 and an outlet compartment 62. For maintaining air flow through the housing and filter a fan is desirable, and it may be near either end of the air passage, preferably 65 at the inlet end. Thus, mounted in an opening in the partition wall is a cylindrical fan casing wall 64 in which is located an air driving fan 65 operated by a motor 66 mounted on a cross bracket 67. This arrangement serves forcibly to 70 draw air in through port 55 and drive it through the filtering element and thence downwardly into the enclosure 10. By employing a fan 75 in the enclosure 10 which is sufficiently powerful and properly arranged to such air through both 75

inlets 19 and 20, a separate filter fan may be unnecessary.

The filter element 70 may be composed of any desired material or layer which is pervious to air but operates to obstruct the passage of solids and thus strain and remove them from the air. Thus the filter 70 may be composed of a suitable fabric such as Australian wool matted or felted into the proper shape. It may contain chemicals 10 to remove acid or other non-solid constituents.

Instead of a flat sheet of filtering material the filter 70 is shown as of enlarged, chambered or cylindrical form, preferably open at but one end, and enclosing a filter chamber, thus presenting 15 a very large surface for the passage of air from within the filter chamber to the compartment 62, and minimizing the need of interchange or cleaning of the filter element. In order to hold the filter element in the cylindrical or chambered 20 form shown, it is mounted upon a light but stiff wire cage 71 constituting a supporting bracket; and the filter element and the wire cage are shown both attached to a circular flange 72 outstanding from the partition wall 60.

25 The operation, which has been indicated, may be explained further as follows. The vessel 16 and the tank 38 may each be assumed to hold a substantial quantity of water, as 50 gallons or more each, being interconnected by the pipes 39 and 40 for summer use. The tank also is assumed to be connected with cooling or refrigerating means tending to cool the water to a point substantially below 50°, or nearly to 40°. The refrigerating of the tank need not be continuous 30 but may be discontinued before retiring, the existing coolness of the water serving to carry the action through the sleeping period of the night. The cool water in the tank passes through pipe 40 into the vessel by automatic gravity circulation, the warmer water in the vessel passing back by pipe 39 into the tank. This gravity circulation between vessel and tank is cooperative with a local circulation within the vessel produced by the rotation of the partially submerged 35 45 air treating rotary element or wheel 32, the wheel being turned by the forcible flow of air above the water level, and the turning of the wheel gently propelling the water within the vessel, so as constantly to bring fresh water to the point 50 of submergence. These two automatic circulation operations cooperate to the improvement of efficiency, the pipe 40 bringing fresh cool water into the path of the current leading to the rotary element 32, and the water passing from 55 the rotary element traveling toward the pipe 39 which returns the relatively warmer water to the tank.

Outdoor air in measured restricted quantities is drawn into the filter housing and combined 60 with recirculated indoor air, either before filtering or afterward, or both as shown. The air is caused to pass through the filtering layer removing pollen and other solids and constituents, passing thence into compartment 62 and down- 65 wardly into the inlet end of enclosure 10. The fan within the enclosure draws air not only through the filtering apparatus, including a proportion of outdoor air, but through the main air inlet 19 for recirculation. The adaptability of 70 the apparatus permits any desired regulation as to recirculation of room air and the steady supplementing thereof with a percentage of outdoor air, the progressive increase in total air thereby maintaining a slight pressure within the room 75 causing the surplus air to find its way out natu-

rally and preventing eventual staleness. The slight pressure maintained in the room is of great advantage in preventing infiltration of outside air carrying dust, pollen, etc.

Within the enclosure the air is not only washed 5 by passing through the rotary element or wheel 32, but is modified to the most suitable temperature and is controlled as to its humidity, being either humidified if too dry, or dehumidified if too moist. By including suitable liquid ingredients in the vessel water, as pine needle oil, the air may be suitably medicated or perfumed. From the outlet 21 the filter washed and temperature and humidity regulated air is delivered gently 10 into the room tending to maintain a slow circulation similar to a light breeze to the advantage 15 of the air condition in the room.

In winter time the auxiliary tank 38 may be put out of operation as described and the water within the vessel 16 may be heated as described 20 to warm and humidify the room air. The volumes of the water vessels 16 and the tank 38 and the depths of water therein may be varied to suit the particular conditions in hand; and each room may be maintained at the temperature and hu- 25 midity best suited to the occupant.

The principles of the described apparatus are well adapted for air conditioning in a closed automobile, permitting a hay fever patient to travel in comfort even through a heavily pollen-laden 30 atmosphere. The water vessel with rotary element and the water tank with cooling means are preferably located outside the rear end of the body, delivering the conditioned air into the upper part of the enclosed space. Fresh and clean out- 35 door air may be drawn from a point near the top of the vehicle and passed thence into the air conditioning vessel above the water therein, and cooled to the proper temperature by circulation from the adjacent tank. The outdoor air may be 40 combined with inside air recirculated from the car, the two being mixed before passing through the conditioning unit, and the conditioned mixture is gently forced into the car near the upper 45 rear corner.

Having described an illustrative air conditioning apparatus embodying the principles of the present invention it is to be understood that the invention is not limited to the features of combination, arrangement and construction as illustrated and described, but covers broadly the features of apparatus and method without restriction except to the extent set forth in the appended claims.

1. For a sleeping room, an air conditioning 55 machine located in said room comprising an enclosure with a water vessel and a fan therein, a partly submerged wheel rotatable in said enclosure, a casing enclosing an air passage occupied by the unsubmerged portion of said wheel, 60 an air inlet for receiving air directly from said room, an air outlet delivering air to said room, a filter housing containing a second fan and a filter, with damper controlled air intakes from outdoors and indoors to said filter, an air outlet 65 from said filter housing for delivering air to said enclosure, a cold water tank located in a housing separated from said enclosure, and having a vent delivering outside said room, circulating pipes connecting the upper and lower portions of said 70 tank and vessel, and a refrigerating coil in said cold water tank.

2. An air conditioning apparatus of the kind having an enclosure containing a water vessel and thereabove an air passage with a fan maintaining 75

air flow through the enclosure and a movable means or wheel alternately entering the water vessel and the air passage for causing treatment of the air stream by the water, such apparatus 5 comprising in combination therewith a separate water tank for water of different or lower temperature than that in the vessel, and high and low water connections between the tank and vessel for circulation as between the vessel and tank 10 and thereby control of the water temperature in the vessel; together with a filter housing containing an air filter and having an independent air propelling means, a duct for supplying restricted outdoor air to the filter, and a port delivering the 15 filtered air to the enclosure.

3. An air conditioning apparatus of the kind having an enclosure containing a water vessel and thereabove an air passage for air flow through the enclosure and a movable means alternately 20 entering the water vessel and the air passage for causing treatment of the air stream by the water, such apparatus comprising in combination therewith a supplemental water tank having means for controlling the temperature of the water 25 therein, and circulation connections between the tank and vessel for interflow of water between them, the water having the same level in said tank and vessel, a filter housing separate from the enclosure and with an outlet port delivering to the enclosure, a partition dividing the housing into inlet and outlet 30 compartments, and supporting a filter, an outdoor air duct leading to the inlet compartment, with damper means to control the rate of outdoor air intake, and two separate 35 rate air forcing means one for causing continuous air flow through the filter housing and the other in the enclosure.

4. An air conditioning apparatus of the kind having an enclosure containing a water vessel 40 and thereabove an air passage for air flow through the enclosure and a movable means or wheel alternately entering the water vessel and the air passage for causing treatment of the air stream by the water, such apparatus comprising 45 in combination therewith means for controlling the temperature of the water in the vessel, a filter housing separate from the enclosure and with an outlet port delivering to the enclosure, a partition dividing the housing into inlet and outlet 50 compartments, and supporting a filter, an out-

door air duct leading to the inlet compartment, with damper means to control the rate of outdoor air intake, and air forcing means for causing continuous air flow through the filter housing and enclosure, comprising a fan in the enclosure 5 and a second fan at the inlet end of the filter housing.

5. An air conditioning apparatus of the kind having an enclosure containing a water vessel and thereabove an air passage for air flow through the enclosure and a movable means or wheel alternately entering the water vessel and the air passage for causing treatment of the air stream by the water, such apparatus comprising in combination therewith means for controlling 10 the temperature of the water in the vessel, a filter housing separate from the enclosure and with a port delivering therefrom to the enclosure, the enclosure having also a direct indoor air inlet, a partition dividing the housing into inlet and outlet 15 compartments, and supporting a filter, an outdoor air duct leading to the inlet compartment, with damper means to control the rate of outdoor air intake, and air forcing means for causing continuous air flow through the filter 20 housing enclosure.

6. Apparatus as in claim 5 and wherein the housing inlet compartment has not only an outdoor air inlet but an indoor air inlet.

7. An air conditioning apparatus of the kind 30 having an enclosure containing a water vessel and thereabove an air passage for air flow through the enclosure and a movable means or wheel alternately entering the water vessel and the air passage for causing treatment of the air stream 35 by the water, such apparatus comprising in combination therewith means for controlling the temperature of the water in the vessel, a filter housing separate from the enclosure and with an outlet port delivering to the enclosure, a partition dividing the housing into inlet and outlet 40 compartments, and supporting a filter, an outdoor air duct leading to the inlet compartment, with damper means to control the rate of outdoor air intake, and air forcing means for causing 45 continuous air flow through the filter housing and enclosure; the filter housing resting removably upon the enclosure with its outlet end above the inlet end of the enclosure.

CHARLES B. GRADY. 50
